Design No. 12,071, dated December 21, 1880.

UNITED STATES PATENT OFFICE.

GEORGE W. ARCHER, OF ROCHESTER, NEW YORK, AND GEORGE W. LYON,
OF CHICAGO, ILLINOIS.

DESIGN FOR A PIANO-STOOL.

SPECIFICATION forming part of Design No. 12,071, dated December 21, 1880.

Application filed August 24, 1878. Term of patent 7 years.

To all whom it may concern:

Be it known that we, GEORGE W. ARCHER, of Rochester, Monroe county, New York, and GEORGE W. LYON, of Chicago, Cook county, Illinois, have invented or produced a new and original Design for Piano-Stools; and we do hereby declare that the following is a full, clear, and exact description of the same, reference being had to the accompanying photographic picture, which shows the piano-stool in perspective.

Our design has relation to the legs of the stool, and is as follows:

A represents the standard, which is octagonal in cross-section, and has a turned cap, D, at top and bottom.

B B B are the four legs, which stand radially from the standard. Each of these legs consists of a curved lower portion, g, and a straight vertical portion, p, which is square in cross-section, and at the top of which is a square cap, k, which is of greater diameter than the leg, so that it projects at the edges, forming a cover. On top of the cap is a turned stud, l, and on the outer edge of the vertical

portion p is a similar stud, m. On the inner side of the leg, where it joins the standard, is a web, f, having at top and bottom scrolls h i, standing reversely to each other, as shown.

The leg above described, having a curved foot standing outward and a square vertical portion above the foot, surmounted by a square cap, and with the reverse scrolls on the inner side, where it joins the standard, presents a highly-ornamental appearance. 35

What we claim as new is—

The design for a piano-stool, consisting of the octagonal standard A and legs B, having the curved feet g, the square upper vertical portions, p, the square caps k, and the webs f, 40 having reverse scrolls h i at top and bottom, as herein shown and described.

In witness whereof we have hereunto signed our names in the presence of two subscribing witnesses.

GEO. W. ARCHER.
GEORGE W. LYON.
